Application December 17, 1929, Serial No. 414,749
Renewed September 27, 1933

35 Claims. (Cl. 240—41.3)

This application is a continuation in part of my application Serial No. 380,281, filed July 23, 1929.

In that application I have disclosed a headlight for motor cars, or the like, which prevents the formation of stray, or dazzling rays in the beam of the headlight, and have shown an arrangement in which part of the rays of the issuing beam diverge below the horizontal, so as to 5 light parts of the road adjacent the vehicle, and without producing a glaring effect upon the drivers of vehicle coming in the other direction. Such application also discloses means for giving 10 indications of the position of the vehicle to the drivers of following vehicles.

My present application is directed more particularly to improvements in the optical characteristics of the headlight disclosed in my prior application, and to improvements in the construction, combination and arrangement of the parts 20 of such headlight.

One of the objects of my present invention is to improve the construction of the lamp and condenser lens mounting.

25 Another object is to provide an improved construction of the modified Fresnel lens and the optical system, whereby the concentrated portion of the beam is brought into its most useful position therein, and whereby the divergent part of 30 the beam is improved in intensity and uniformity of spread.

With these and other objects in view, which will become apparent as the description proceeds, the invention resides in the construction, combination and arrangement of parts hereinafter 35 more fully described and claimed.

In the drawings forming part of this specification,—

40 Figure 1 represents a vertical central sectional view taken through a headlight constructed according to my invention.

Figure 2 represents a detail horizontal sectional view on a larger scale through the lamp casing.

45 Figure 3 represents a front face view of the main lens.

Figure 4 represents a rear face view thereof.

Figure 5 represents a fragmentary horizontal sectional view through the lens.

50 Figure 6 represents a fragmentary vertical perspective view thereof.

Figure 7 represents a vertical section through the lens, showing the construction thereof.

Figure 8 represents a similar view of a modified form.

Figure 9 represents a vertical section of the lens of Figure 7, showing the light distribution.

Figure 10 represents a similar view through the lens of Figure 8.

Figure 11 is a view showing the use of the condenser lens and mirror in the optical system.

Figure 12 represents a vertical section on a small scale through the beam projected by the lens of Figure 9, taken at a distance from the lens.

65

Figure 13 represents a similar view of the beam projected by the lens of Figure 10.

Figure 14 represents a top plan view of the lamp-supporting bracket, removed.

Referring more particularly to Figures 1 and 2 of the drawings, the headlight includes a metallic casing A, of general ellipsoidal form, or of other form if desired, having a forward section 5 and a rear section 6, which are separable from each other, the forward section being shouldered 75 vertically and circumferentially of the headlight as at 7, to receive the forward edge of the rear section which fits over said shoulder. The sections are removably retained together by means of thumb screws 8, the threaded shanks of which 80 pass through openings provided in the rear half of the casing into engagement with internally threaded sleeves 9 screwed into ears 10 which may be cast with the forward section of the casing, the concave washers 11 being interposed 85 between the thumb screws and casing to frictionally retain the former in position against accidental unscrewing. When the thumb nuts are unscrewed and removed, the rear section of the casing may be slipped off of the shoulder 7 to expose the parts of the headlight contained within 90 in the casing.

Within the casing there is carried an angularly disposed bracket B, which may be a casting, having a tripod support comprising three lugs 12 95 adapted to fit against the upper of corresponding sets of lugs 13 which may be cast upon the upper and the lower inside portion of the front casing section, the tripod lugs being retained in place by screws and washers 14. The bracket B 100 is shown as supported upon the upper set of lugs by its tripod connection, but, if desired, it may be removed from the upper set, turned upside-down, and supported upon the lower set.

The bracket B at its lower end, is provided 105 with a rearwardly extending centrally located ring 15, and flanking this and forward of it, a pair of rings 16, such rings being adapted to receive lamp sockets 17, the lamp 18 mounted in the middle or centrally located socket being 110

used for ordinary driving purposes, and the lamps 19 in the flanking sockets being used, if desired, when dim lights are wanted. Set screws 20 may be utilized to retain the sockets in position. The 5 side lamps need not be used unless desired, and indeed, may, if preferred, be left out of the assembly. The connections to the lamps may be made in any desired manner, the terminals 21 on the lamp sockets being provided for this purpose.

Forward of the lamp 18 is arranged a ring 22, in which is mounted a condensing lens 23, such ring having arms 24 which straddle the bracket B, and which are secured thereon by means of 15 a pin 25 extending through the side flanges of the bracket and through openings in the arms 24, and one of such arms has an extension 26 which, by means of a screw 27 prevents pivotal movement of the ring on the pin 25 and retains the 20 ring and the condenser lens in a fixed angular position in the optical system of the headlight.

In the opening at the forward portion of the headlight casing is mounted a lens C, the outer flange of which is held in position between the 25 lip 28 at the opening of the casing and the ring 29, at the forward face of the lens flange, and a ring 30 at the rear thereof. An arm 31 extends into a notch at the top of the lens flange for properly positioning the lens in the casing, such 30 arm being retained in position beneath the forward lug 12 of the bracket and its supporting lug 13.

To the rear of the lamp 18 is arranged a spherical reflector 32, and this reflector may be carried by a mounting secured to the central lamp supporting ring 15, or may be supported in other desirable manner. The condensing lens 23 may, if desired, not be used in the optical system of the headlight, and the same is true of 40 the reflector 32, or either may be used without the other. If used, however, they enter into the combination of the optical elements in projecting the desired beam, as will later appear.

Referring more particularly to the optical 45 characteristics of the headlight, the lens C, which is in the general shape of a circular Fresnel, but in which the refracting zones are modified over those of the usual Fresnel, has a spherical front face 35, and on the upper half of its rear face 50 has a series of substantially semi-circular refracting zones 36 and on the lower half another series of substantially semi-circular refracting zones 38, there being also provided a centrally located bull's eye 40. The refracting zones and 55 the part of the bull's eye, in the upper half of the lens, and the zones and the part of the bull's eye in the lower half of the lens, are separated along the line of the abrupt shoulders 41, which extend substantially horizontally and diametrically 60 of the lens across the zones thereof and the bull's eye. The inner corners 37 of the refracting zones of the lower half of the lens are continuous with those of the respective zones of the upper half of the lens, so that the separating 65 shoulders merge with the surfaces at the inner corners 37. Beginning at the merging corners, the shoulders increase in width across the respective zones toward the outer edges thereof, following the increase in thickness of the lower 70 zones radially of the lens over the upper zones, the shoulders thus being substantially triangular in shape, and being substantially horizontally disposed. On the bull's eye, the shoulders separating the upper and lower parts merge with the 75 surface near the center of the bull's eye and in-

crease in width toward the outer edges, following the increase in thickness of the lower half of the bull's eye toward its outer edges.

The refracting zones and the part of the bull's eye in the upper half of the lens have a common 80 principal focal region at X, and are of such curvatures as to project into parallel rays, light originating at such focal region, the upper portion of the bull's eye and the zones being struck from centers c, along the optical axis O—A, forward of 85 the lens with increasing radii as the outer edge of the lens is approached. The lower zones, and the lower half of the bull's eye have a common principal focal region at Y (indicated by the focus of the parallel dotted rays K), a region disposed further from the lens than the focal region X, and are of such curvature as to project, with increasing divergence away from the axis, rays originating at the focal region Y, the lower half of the bull's eye, like the upper half, having its inner 90 face spherical, but being struck with a radius substantially three times as long, and the faces of the lower zones being segments of conic surfaces whose axes coincide with the optical axis of the lens. The dotted line e in Figure 7 indicates the 100 base of the generating triangle of one of the lower zones, the line d the hypotenuse, and the distance f along the optical axis indicates the altitude of the generating triangle. The angle opposite the axis in the form shown, for instance, may be 105 approximately 5°.

With this construction of the lens, and with the light source at the principal focal region of the upper zones and upper half of the bull's eye, such parts will project light originating at such source 110 into parallel rays, as indicated at g (Figure 9), while the lower zones and lower half of the bull's eye will project rays of increasing divergence away from the axis as the outer edge of the lens is approached, as indicated by the rays i, the rays near 115 the central portion of the lower half of the bull's eye being parallel to the axis as at h, and the rays projected through the outer portion of the last zone of the series on the lower half being of the greatest spread or divergence, such gradually increasing spread being accomplished, in connection with the structure of the lower half of the lens, by the location of the light source not at the principal focal region of the lower part of the lens, but at the principal focal region of the upper part 125 thereof.

On the lower half of the lens, and on opposite sides of the central portion of the front thereof, are arranged a series of vertically disposed cylindrical flutes 42, to laterally spread the light rays 130 passing through the end portions or segments of the lower refracting zones on the opposite sides of the central lower portion of the lens. Such flutes may be struck with equal radii upon centers 135 equally spaced angularly about a common point on the optical axis as indicated in Figure 5.

The resultant beam projected by this optical system, as indicated in Figure 12, is of high intensity in its upper section, as at Q, being composed therein of parallel rays projected through 140 the upper half of the lens, and which reach to distant points on the roadway. In its lower section, which is abruptly widened horizontally over the upper section, as at r, the beam comprises the lateral portions composed of the wide spread rays 145 of less and outwardly decreasing intensity projected through the vertical flutes, and which illuminate the sides of the roads and adjacent gutters or side-walks. The central portion T of the lower section of the beam, of higher intensity 150

- than the portion S, which is projected through the lower lens section between the fluted portions thereof, illuminates the roadway with decreasing intensity as the front of the vehicle is approached.
- 5 All of the upper half of the lens enters into the formation of the intense parallel rays for distant illumination and the lower half forms the illumination of greater width, with decreasing intensity towards the vehicle and with increasing spread 80 towards the sides of the lower portion of the lens. The spread obtained by the fluted sections, added to that obtained in the central portion of the lower lens section, may give to the lower section of the beam a total spread of as much as 75°, if desired, depending upon the curvatures used, an adequate spread for efficiently lighting the roadway and bordering side-walks and gutters.
- 10 The spherical reflector, when utilized with the optical system, as indicated in Figure 11, is preferably arranged with its focus at the principal focal region X of the zones and bull's eye of the upper half of the lens, to increase the light flux projected through the lens, and, if the condensing lens 23 is used, the latter has its optical axis o—a 85 25 preferably arranged at an angle with the optical axis of the system, with the top of the condenser inclined forwardly away from the light source, to thereby condense the light passing through the Fresnel below the upper zones, to increase the intensity of lower portions of the light beam, as indicated in dotted lines at l, m.
- 30 In the form of the system shown in Figure 8, the shape of the bull's eye is somewhat changed, the lower half having its principal focal region 35 at Z, between the principal focal region X' of the upper part of the lens and bull's eye and the principal focal region Y' of the lower zones, and the radius of the upper part of the bull's eye is increased and is struck from a point below 40 the optical axis, so that, as shown in Figure 10, with the light source at the principal focal region X', the upper part of the bull's eye will project rays n which, as the optical axis is approached, will converge toward and cross such axis, and 45 the lower part of the bull's eye, will project rays which are parallel adjacent the optical axis, and which diverge as the points of projection are removed from the axis. Thus, the rays which 50 from the upper part of the bull's eye converge and cross the axis will fall at angles below the horizontal, to thus lower the position of the so-called "hot spot" in the projected beam, as indicated at V in Figure 13, and in crossing the parallel rays projected by the portion of the lower 55 half of the bull's eye adjacent the axis, will intensify the upper central part of the lower section of the beam, as shown. I also so shape the lower zones as to cause the light rays projected through them to cross each other with 60 equal degrees of spread for the various zones, with the light projected through one of such zones overlapping that projected through adjacent zones, as indicated by the rays b—c in Figure 10, such zones being struck from centers p 65 (Figure 8), arranged at decreasing distances below the axis and with decreasing radii, as the outer edge of the lens is approached (except for the outermost zone), and with such exception being of cylindrical curvature of decreasing radii 70 radially of the lens. The outermost zone is preferably struck with a somewhat longer radius than the next adjacent zone to bring its projected light well to the edge of and define the lower section of the beam. The rays from each of the lower 75 zones thus crossing, and overlapping the projec-

tion from adjacent zones, the uniformity of light in the beam projected by the lower part of the lens is increased, as indicated by the cross hatching on Figure 13, and at the same time the spread or dispersion of the lower part of the beam is retained. In this form of the invention, the upper zones merge with the respective lower zones at their outer edges, the thickness of the upper zones increasing from their outer edges inwardly with respect to the respective lower zones, and the abrupt shoulders (see 41'—Figure 8) are reversed in position, being wider at the inner edges of the zones and narrowing toward their outer edges.

85 90 Since this application was filed, I have filed applications Serial Nos. 428,876, and 554,111, both of which applications disclose subject-matter common to this application and to my application, Serial No. 380,281. In this application, however, I am making the broader claims to the modified Fresnel lens disclosed in my said applications, as well as claims to various structural features thereof, and to the combination of such lens with the condenser, and also the arrangement in which the light source is arranged at 100 one of the focal regions of the lens, claims to other subject-matters being made in my other applications.

95 100 The foregoing detailed description has been given for purposes of illustration of my invention, and no undue limitation should be deduced therefrom, it being understood that such variations in the construction, combination and arrangement of parts, are permissible as do not depart from the spirit of the invention and the 110 scope of the appended claims.

I claim:—

1. In a light projector, a modified Fresnel lens having a spherical front face, and on its rear face having circular stepped refracting zones, the 115 zones on the upper half of the lens having a principal focal region, a light source substantially at said focal region, the zones on the lower half of the lens having a focal region differing from that of the zones on the upper half and being of 120 such curvatures as to disperse light falling on them from the light source, the angles of dispersion gradually increasing from the axis outward, a line of abrupt shoulders extending substantially horizontally and diametrically across 125 the lens between the zones, the zones on the lower half being of longer focal length than the zones on the upper half of the lens.

2. In a light projector, a modified Fresnel lens having on its rear face an upper set of stepped zones of decreasing curvature outwardly and radially of the lens, such zones having a principal focal region, and having a lower set of stepped zones differing in curvature from the upper zones and having a focal region displaced from that of the upper zones and being of such curvatures as to disperse light falling thereon from their focal region, the angles of dispersion increasing from the axis outward, and a line of abrupt shoulders extending substantially horizontally and diametrically of the lens and separating the upper and lower zones, in combination with a light source arranged substantially at one of said focal regions.

130 135 140 145 150 3. In a light projector, the combination of a modified Fresnel lens having a convex front face and on its rear face having circular stepped refracting zones and a centrally located bull's eye, the zones and bull's eye on the upper half of the lens having a principal focal region, the

- zones and bull's eye on the lower half of the lens having a focal region, and being of such curvature as to disperse light falling on them from such focal region, the angles of dispersion gradually increasing from the axis outwardly, a line 5 of abrupt shoulders extending substantially horizontally and diametrically of the lens across the bull's eye and zones, the zones and bull's eye of the lower half being of longer focal length than the zones and bull's eye of the upper half of the lens, in combination with a light source arranged substantially at the principal focal region of the zones and bull's eye of the upper half. 10
4. In a light projector, the combination with a modified Fresnel lens having a convex front face, and on its rear face having circular stepped refracting zones and a centrally located bull's eye, the zones in the upper half of the lens and the upper half of the bull's eye having a 15 principal focal region, and the zones of the lower half of the lens having a focal region displaced from that of the upper lens and being of such curvature as to disperse light falling on them from their focal region, the angles of dispersion of the lower zones gradually increasing 20 from the axis outward, a line of substantially horizontally disposed shoulders extending substantially diametrically of the lens, such shoulders differing in width between the inner and outer edges of the zones, the zones of the lower half of the lens being of longer focal length than the zones and bull's eye of the upper half, in combination with a light source arranged substantially 25 at the principal focal region of the zones and bull's eye of the upper half of the lens. 30
5. In a light projector, the combination of a modified Fresnel lens having a convex front face and having on its rear face an upper set of stepped zones of decreasing curvature outwardly and radially of the lens, and a lower set of stepped 35 zones differing in curvature from the zones of the upper set, a line of abrupt shoulders extending substantially horizontally and diametrically of the lens separating the upper and lower zones, a central bull's eye of different curvatures in its upper and lower portions, the upper zones having a 40 principal focal region, and the lower zones having a focal region displaced from the focal region of the upper zones, and a light source arranged substantially at the principal focal region of the 45 upper zones. 50
6. In a motor vehicle headlight, the combination of a modified Fresnel lens having a spherical front face and having on its rear face an upper set of stepped zones of decreasing curvature outwardly and radially of the lens and a lower set of stepped zones of conic segmental form, a line 55 of abrupt shoulders extending substantially horizontally and diametrically of the lens separating the upper and lower zones, a central bull's eye of different curvatures in its upper and lower portions, sets of vertical cylindrical flutes on the forward face of the lens extending not higher than the line of shoulders and disposed on opposite sides of the lower central portion of the lens, the upper zones having a principal focal region 60 and the lower zones having a focal region displaced from the focal region of the upper zones, and a light source arranged at the principal focal region of the upper zones. 65
7. A modified Fresnel lens having upper and lower sections, the upper section having substantially semi-circular stepped zones of decreasing curvature outwardly and radially of the lens, and the lower section having substantially semi-circular stepped zones of increasing curvature outwardly and radially of the lens, the curvature of the zones of one section differing from the curvature of the zones of the other section, the focal length of one lens section being different from the focal length of the other lens section. 80
8. A modified Fresnel lens having an upper set of refracting zones and a lower set of refracting zones, the zones of the lower set varying in curvature among themselves and differing in refractive powers from the zones of the upper set, and being struck with radii from different centers arranged at decreasing distances below the axis of the lens and with decreasing length of radius as the outer edge of said lens is approached. 85
9. A modified Fresnel lens having upper and lower sections, each formed with refracting zones of varying curvatures, the upper section having a focal region different from that of the lower section, the curvature of the zones of one section differing from the curvature of the zones of the other section and a centrally located bull's eye, part of said bull's eye having a focal region between the focal regions of the upper and lower sections of the said lens. 95
10. A modified Fresnel lens having upper and lower sections, each formed with refracting zones varying in curvature, a centrally located bull's eye divided into upper and lower parts, the upper section and the upper part of the bull's eye having a focal length different from that of the lower section and the lower part of the bull's eye, the curvature of the zones of one section differing from the curvature of the zones of the other section. 105
11. A modified Fresnel lens having an upper section and a lower section, the upper section being formed with refracting zones differing in curvature with respect to each other, the lower section of the lens being formed with refracting zones differing in curvature with respect to each other and to the zones of the upper section, a centrally located bull's eye divided into upper and lower parts, the radius of the upper part of said bull's eye being struck from a point below 110 the optical axis of the lens. 120
12. A modified Fresnel lens having an upper set of refracting zones and a lower set of refracting zones, the zones of the lower set varying in curvature among themselves and differing in refractive powers from the zones of the upper set, each zone being struck with a radius from a different center, and a centrally located bull's eye, part of said bull's eye being struck with a longer radius than the zones of the lens. 125
13. In a light projector, a modified Fresnel lens having upper and lower sections each formed with refracting zones varying in curvature with respect to each other, and with respect to the zones of the other section, a light source, the upper section projecting rays from said light source into a substantially horizontal beam, and the lower section projecting rays from said light source downwardly and laterally, the zones of the lower section being struck from centers arranged at decreasing distances below the axis of the lens, and with decreasing radii whereby the light rays from the various lower zones will cross each other with substantially equal degrees of spread, and the rays projected through one zone will cross those projected through adjacent zones. 135
14. A modified Fresnel lens having upper and lower sections, each formed with refracting zones, the zones of the upper section being of varying curvature and differing from the zones 140
- 75

- of the lower section, the rear faces of the zones of the lower section being substantially segments of conic surfaces having axes of rotation substantially coinciding with the optional axis of the lens. 21. In a light projector, the combination of a modified Fresnel lens having an upper and a lower set of refracting zones, with the refracting zones of the upper set varying in curvature with respect to each other and with respect to the refracting zones of the lower set, a light source, and a condensing lens interposed between said Fresnel lens and said light source. 80
15. A modified Fresnel lens having an upper section and a lower section, the lower section being formed with refracting zones differing in curvature with respect to each other, the upper section of the lens being formed with refracting zones differing in curvature with respect to each other and to the zones of the lower section, the zones of the upper section merging with the respective zones of the lower section at their outer edges and being increased in thickness inwardly with respect to the respective zones of the lower section and forming shoulders between the zones of the upper and lower sections. 22. A light projector including in combination, a modified Fresnel lens having a spherical front face and having on its rear face an upper set of stepped zones of different curvatures outwardly and radially of the lens, and a lower set of stepped zones of different refractive power, a bull's eye disposed centrally of the lens, a series of vertical cylindrical flutes on the front face of the lens extending below the horizontal axis of the lens, the lower refracting zones having a common focal region different from the focal region of the upper refracting zones beyond the focal region of the upper zones in a direction away from the lens, and a condenser between said source of light and said lens. 85
16. A modified Fresnel lens having upper and lower sections, each formed with refracting zones, the zones of the one section being of varying curvature and differing from the zones of the other section, the inner corners of the refracting zones of the upper section merging with those of the respective zones of the lower section, and a line of abrupt shoulders separating the upper and lower sections, said shoulders beginning at the merging corners of said refracting zones and increasing in width toward the outer edges of the zones. 23. In a light projector, the combination of a modified Fresnel lens having upper and lower sections, each formed with refracting zones of varying curvatures, the upper section having a focal length different from that of the lower section, the curvature of the zones of one section differing from the curvature of the zones of the other section, a light source, a condensing lens interposed between said Fresnel lens and said light source, and a reflector behind said light source. 90
17. In a light projector, in combination, a modified Fresnel lens divided into an upper section and a lower section of stepped refracting zones of varying curvature and of different power, and a centrally disposed two-halves bull's eye, the zones and the half bull's eye in the upper section of the lens having a focal region, the zones and the other half bull's eye in the lower section of the lens having a different focal region, and a light source arranged substantially at one of said focal regions. 24. A concavo-convex lens comprising two half Fresnel lenses in one unit, the lens halves being provided with refracting zones, the zones of the one half varying in curvature from the zones of the other half, the zones of each half varying in curvature among themselves, the focal length of one lens half being different from the focal length of the other lens half. 110
18. In a light projector, a unitary modified Fresnel lens having upper and lower sections, each formed with refracting zones of varying curvatures, the upper section having a focal length different from that of the lower section, the curvature of the zones of one section differing from the curvature of the zones of the other section, and a line of abrupt shoulders extending substantially horizontally and diametrically of the lens separating the upper and lower sections. 25. In a light projector, a modified Fresnel lens having upper and lower sections each formed with refracting zones of varying curvature, the upper section having a focal length differing from that of the lower section, the curvature of the zones of one section differing from the curvature of the zones of the other section, the lens being formed with flutings, said flutings being struck with equal radii on centers equally spaced angularly about a common point on the optical axis of said lens. 120
19. In a light projector, in combination, a modified Fresnel lens having upper and lower sections, each formed with refracting zones varying in curvature, the upper section having a focal region different from that of the lower section, the curvature of the zones of one section differing from the curvature of the zones of the other section, the lens being formed with flutings, said flutings being struck with equal radii on centers equally spaced angularly about a common point on the optical axis of said lens. 26. A unitary modified Fresnel lens having upper and lower sections, each formed with refracting zones of varying curvature, the upper section having a focal length different from that of the lower section, the curvature of the zones of the one section differing from the curvature of the zones of the other section. 130
20. In a light projector, the combination of a modified Fresnel lens having upper and lower sections, each formed with refracting zones of varying curvatures, the upper section having a focal length different from that of the lower section, the curvature of the zones of one section differing from the curvature of the zones of the other section, a light source in the region of the foci of the sections, a second light source at one side of the first said light source, and a third light source at the other side of said first light source. 27. A modified Fresnel lens divided on the horizontal median line into an upper half and a lower half, the upper half being formed with refracting steps differing in curvature with respect to each other, the lower half of the lens being formed with refracting steps differing in curvature with respect to each other and to the steps of the upper half, each step of the lens being of substantially uniform refractive power. 140
28. A light projector comprising a modified Fresnel lens having a plurality of sections, one of which above the horizontal axial plane has a different focal region from another section below said plane, both the sections of the lens having refracting zones, the curvature of the zones of 145

each of said sections varying relatively to each other and to the zones of the other section, and a light source in the region of the foci, the formation of the refracting zones of the sections of the lens making the projected beam from the lens as a whole relatively insensitive to limited varying relations between the light source and the foci of the lens sections.

29. In a light projector, a unitary modified Fresnel lens having upper and lower sections, each formed with refracting zones of different curvatures, the upper section having a focal length different from that of the lower section, the curvature of the zones of one section differing from the curvature of the zones of the other section, and a light source positioned in the region of the foci.

30. A modified Fresnel lens having an upper section and a lower section, the lower section being formed with refracting zones differing in curvature with respect to each other, the upper section of the lens being formed with refracting zones differing in curvature with respect to each other and to the zones of the lower section, each zone being of substantially uniform refractive power.

31. A modified Fresnel lens having an upper set of refracting zones and a lower set of curved refracting zones, the zones of the lower set varying in curvature among themselves and differing in refractive powers from the zones of the upper set, each complete zone being struck with a radius from a different center.

32. A modified Fresnel lens having an upper and a lower set of refracting zones, the zones of the upper set varying in curvature among them-

selves and being struck with radii from various centers and differing in refractive powers from the zones of the lower set, some of said centers lying substantially on the axis of the lens and some below the axis thereof.

80

33. A unitary modified Fresnel lens having upper and lower sections, each section formed with refracting zones of varying curvature, the upper section having a focal length different from that of the lower section, the curvature of the zones of the one section differing from the curvature of the zones of the other section, the lens being formed with flutings for lateral light diffusion.

85

34. A modified Fresnel lens having an upper and a lower set of refracting zones, the zones of the upper set varying in curvature among themselves and differing in curvature from the zones of the lower set and being struck with radii from various centers, the zones of the lower set being also struck with radii from various centers, some of the latter centers lying substantially below the axis of the lens.

90

35. In a light projector, a Fresnel lens having its rear face divided into an upper set and a lower set of stepped refracting zones, the zones terminating substantially along the horizontal diameter of the lens, the upper set of zones having a principal focal region and the lower set of zones having a focal region displaced from that of the upper set of zones, the zones of the upper set differing in curvature radially of the lens from the zones of the lower set, the zones of each set differing among themselves in curvature radially of the lens.

95

GUSTAVE ALPHONSE MARIE
LAMBLIN-PARENT.
